United States Patent Office

Des. 197,131
Patented Dec. 17, 1963

197,131

BIRD FIGURE WALL PLAQUE OR THE LIKE
John C. Borton, Jr., 403 W. Masonic View,
Alexandria, Va.

Filed July 10, 1962, Ser. No. 70,867

Term of patent 3½ years

(Cl. D29—23)

Fig. 1

Fig. 2

FIGURE 1 is a top plan view of a bird figure wall plaque or the like showing my new design;

FIGURE 2 is a top plan view of FIG. 1 wherein both wings have been turned in the opposite direction;

FIGURE 3 is a top plan view of FIG. 1 wherein the lower wing only has been turned in the opposite direction;

FIGURE 4 is an edge view from the left of FIGURE 5;

FIGURE 5 is a top plan view of FIG. 1 wherein the upper wing only has been turned in the opposite direction;

FIGURE 6 is a bottom plan view of FIG. 1; and

FIGURE 7 is a bottom plan view of FIG. 2.

I claim:

The ornamental design for bird figure wall plaque or the like, substantially as shown and described.
